UNITED STATES PATENT OFFICE.

FRANK D. SHEPHERD, OF AURORA, ILLINOIS.

PUPPET-VALVE FOR INTERNAL-COMBUSTION ENGINES.

1,331,826.

Specification of Letters Patent. Patented Feb. 24, 1920.

Application filed August 27, 1919. Serial No. 320,273.

To all whom it may concern:

Be it known that I, FRANK D. SHEPHERD, of Aurora, Illinois, have invented a certain new and useful Improvement in Puppet-
5 Valves for Internal-Combustion Engines, and do hereby declare that the following is a full, clear and exact description thereof.

My invention relates to puppet valves for internal combustion engines. I have discovered that localized wear of the valve 10 stem, with consequent cocking of the valve and its failure to seat properly, is due to lateral deformation or buckling of the fairly long coil spring commonly used to 15 move the valve to its seat, which results in side pressure, and my object, generally stated, and primarily, is to prevent the unbalanced side pressure on the stem and thus avoid the localized wear which is objectionable, not only in itself, but in its results in 20 impairing the efficiency of the engine and wasting fuel, and preventing that quick seating of the valve by the spring which is so important. I have also had in view such 25 construction of parts as will most efficiently attain such object and will be best suited for the purpose from the standpoint of the manufacturer and the repairer.

My invention consists in the construction 30 as a whole and in the parts thereof substantially as hereinafter specified and claimed.

In the accompanying drawings:

Figure 1 is a vertical section of a gas engine to illustrate one embodiment of my 35 invention;

Fig. 2 is a vertical section showing a form of my invention in which the container and guide is mounted and placed differently, from what is shown in Fig. 1;

40 Fig. 3 is a detail end view;

Figs. 4 and 5, are, each a similar view of another embodiment of my invention;

Fig. 6 is a detail view in cross section on line 6—6 of Fig. 5;

45 Fig. 7 is a side view of the spring guide or container of Fig. 5.

My invention is not limited in its application to any particular construction of engine so that the latter may be of an L-head or T-head type, with an integral or detachable head. I illustrate my invention in the drawings as applied to an engine of an L-head type, and to engines with detachable and integral heads. The valve mechanism

55 may be the same for both intake and exhaust, but in Fig. 1, I show an engine in which it is applied only to the exhaust. As my invention is not concerned with the valve lifting mechanism, I illustrate the well known cam device for that purpose.

60 In the drawings 10 designates the cylinder, 11 the piston therein, 12 the head which may be detachable as shown in Figs. 1 and 2, or integral as shown in Fig. 4, 13 the valve seat, 14 the valve head for controlling 65 communication between the cylinder 10 and the chamber 15, (either the intake or the exhaust) and 16 the valve stem having its free end reaching to a point where it can be engaged by the rod or plunger 17, actuated by the cam.

70 The chamber 15 is open throughout its length from the valve seat 13 to its opposite end and within the same and beyond the port 18 which leads into or from the chamber 15 is a tubular or cylindrical hollow body 19. The valve stem 16 passes centrally through the body 19, and has a sliding fit within a guide therein. At the lower end thereof, or the end farthest from the 75 valve 14, the stem has a disk or collar 20, upon it to form a thrust bearing for one end of a coil spring 21, that surrounds the valve stem and the valve stem guide within the body 19 that extends down from the 80 head 22, and whose other end has a thrust bearing against head 22. The spring acts to hold the valve head 14 against its seat and when lifted by the cam, it returns to 85 its seat when the cam permits it.

90 To check and prevent any buckling or sidewise deformation of the spring, I give its coils such external diameter relative to the internal diameter of the body 19 that at the time of greatest compression of the 95 spring, which is the time the valve is off its seat, such coils will engage the interior of the body and thereby be restrained from buckling and compelled to act upon the valve stem in a direction wholly parallel 100 with its length.

To compensate, or allow for any expansion of the coils of the spring when compressed as the result of lifting the valve from its seat, I make the coils of such diameter that when the spring is thus compressed, its coils will engage with the inclosing body 19 and it is when the valve

is off its seat and the spring is compressed that any tendency of the spring to buckle must be resisted.

The disk 20 has a sliding fit against the interior of the cylindrical body 19 and an extended bearing thereagainst so as to effectually resist any tendency of the spring 21 to cause sidewise pressure or cocking or tipping of the disk that would result in wedging or binding and thus offer unusual resistance to free movement of the disk, and of the valve stem, with which the disk is connected as hereinafter explained, so that pressure of the spring is transmitted to the stem, or movement of the stem, when lifted by the cam, is transmitted to the disk. The disk has a central hole 23 through which the valve stem passes, said hole being sufficiently larger than the valve stem as to leave a clearance between the sides of the hole and stem, and thus allow side play of the parts without contact of stem and disk. This makes unnecessary the accurate, and, hence, costly fitting of the parts which would be necessary did the disk have a snug or close fit upon the stem. With a snug or close fit of disk and stem, should there be any want of alinement or concentricity of the stem-guiding hole in the body 19 and the disk-engaging interior of the body 19, obviously close fit of stem and disk hole would result in binding of the parts after assembled and in operation and, hence, accuracy of fitting of the parts even to the thousandths of an inch would be necessary.

The disk 20 has a main or web portion which contains the hole 23 through which the stem passes, and as shown in Figs. 1 and 2, an upwardly extending flange or rim 24 and as shown in Figs. 2, 4 and 5 a downwardly extending flange or rim 25 to give an elongated bearing on its periphery against the interior of the body 19.

The hole 23 is made so large that a substantial space exists between the wall thereof and the stem, so that even should wear and side play of the disk occur, it would not reach and exert pressure on the stem. As a gas-tight fit of the stem in the stem guide 45 is provided, the presence of the large hole 23 in the disk, leaving a space around the stem, is not objectionable for no air passing through the hole can enter and injure the charge flowing to the cylinder past the open intake valve. That is to say, between the valve and the intake port and the disk the stem passes through a gas-tight guide hole. The connection between the disk 20 and valve stem by which they move together 55 is in the form of a cross pin or key driven through a hole in the stem, or engaging a groove in the stem and projecting on opposite sides of the stem and engaging the underside of the disk web, as in Fig. 4, or a washer, so that the pressure of the spring

keeps the disk or washer in contact with the projecting ends of the key, so that at all times the disk moves with the stem.

As shown in Figs. 1, 2 and 3, a washer having a close fit upon the valve stem engages the underside of the disk web and the underside of the washer is engaged by a diametrically extending pin 27 passed through the stem and projecting on opposite sides thereof and seated at its projecting ends in a diametrically extending groove or recess 28 in the underside of washer 26. The pin may be rectangular in cross section as shown in Fig. 2, or it may be round as shown in Fig. 1. While the washer has a close fit upon the valve stem there is a clearance between its periphery and the downwardly extending flange 25 of the disk 20 which permits such relative sidewise movement of the disk 20 and stem as may be necessary to compensate for any irregularity of alinement of the parts.

As shown in Figs. 4, 5 and 6, the key is in the form of a U-clip 29 that straddles the stem, and is seated in an annular groove 30, 90 therein.

To facilitate the insertion and removal of the pin or key, the guide or container 19, at its bottom, has diametrically opposite notches 190, of a size to permit the passage 95 of the pin or key, the disk 20 and washer 26, of course being pressed up in the guide to expose these notches. The initial pressure of the spring on the valve results from this key-inserting operation.

Preferably as shown in each of Figs. 1, 2, 4 and 5, the periphery of the disk is provided with one or more small annular grooves 31 to receive a lubricant.

It will be seen that in each form of my invention that as far as turning movement is concerned there is a loose connection between the disk and the stem so that the valve head 14 is free to turn with reference to its seat, and will not always contact with its seat in the same position, and thus localized wear on valve and seat and leakage is prevented.

Preferably the wall of the body 19 is provided with openings or perforations which may be mere holes 32 as illustrated in Figs. 2, 4 and 5, or elongated openings or slots 33 as illustrated in Fig. 1, these openings or perforations serving the purpose of allowing the free passage of air so as to avoid any interference with the free action of the valve, and for supplying oil to the interior of the body 19. The slot form of opening is an advantage in that it makes a lighter construction.

In the embodiment of my invention illustrated in Fig. 4, the body or member 19 is secured in place by having at its upper or inner end an annular flange or shoulder 34 which engages a seat 35 on the wall of the

chamber 15, and a lock ring or nut 36 which engages thread on the exterior of the body 19 and abuts against the surfaces around the open outer end of the chamber 15. In some cases, however, as in small engines with a light exhaust, the shoulders 34 and 35 may be omitted and in place of the lock ring 36 an integral flange 37 (see Fig. 5) may be provided to engage the surface adjacent the open end of the chamber 15, the portion of the body or member 19 within the chamber 15 having a tight fit therein. In this last-named case, the pressure of the spring 21 against the head 22, of the body 19, is in the direction to keep the body in place.

In Fig. 2, the body 19 instead of having a friction fit within the chamber 15 has a screw thread connection therewith.

As shown in Fig. 1, the members of the body or member 19 may be made in one piece and a friction connection made between the portion of the body within the chamber and the wall of the latter around said portion.

As shown in Figs. 1 and 2, a single spring is employed. However, I may use, and in some cases may find it desirable to use more than one. In each of Figs. 4 and 5 I show, besides the spring 21, a second coil spring 38, concentric with and inside the spring 21. In Fig. 4 the pitch of the coils of both springs is in the same direction, and the inner spring is restrained from buckling and interlocking its coils with the outer spring by an internal tubular extension 39 of the body or member 19. In Fig. 5 the pitch of the coils is opposite, and as thereby interlocking of coils is prevented, I use the outer spring as the means to prevent buckling of the inner spring by making their diameters such that on compression when the valve is lifted, the coils will have peripheral contact. By multiplying and nesting the springs, the coils can be of lighter gage than when a single spring is used, and in consequence the two springs are more flexible, and quicker to act, and that means closer following of the cam and quicker seating of the valves, and consequently increase of efficiency of the engine.

It is to be understood that the elements going to make up the construction shown in any one figure of the drawings may be differently combined. For example, for the single spring shown in Fig. 1, may be substituted the double spring shown in Fig. 4, and for the spring-engaging disk construction shown in Fig. 5 may be substituted the spring-engaging disk construction shown in Fig. 1.

What I claim is:

1. In an internal combustion engine, the combination of a valve, having a stem, a valve stem guide, an expansively acting coil spring surrounding the stem having a fixed bearing at one end, a bearing for the other end of the spring to transmit pressure from

the spring to the stem through which the stem passes, a clearance space existing between the stem and the bearing that permits relative lateral movement of the bearing without contact with the stem, a loose connection between the bearing and the stem that permits such lateral movement, said bearing having guiding contact with said guide, the coils of the spring engaging with the guide sides when the spring is compressed, and the valve is off its seat, whereby the spring is restrained from lateral deflection. 70

2. In an internal combustion engine, the combination of a valve having a stem, controlling communication between the cylinder and a chamber, a valve stem extending from the chamber through a hole in which it has a sliding gas tight fit, a spring surrounding the stem and acting at one end against a stationary part, a bearing for the other end of the spring to transmit pressure from the spring to the stem through which the stem passes, a clearance space existing between the stem and the bearing that permits relative lateral movement of the bearing without contact with the stem, a loose connection between the bearing and the stem that permits such lateral movement, and a container with which said bearing has sliding contact and with which the coils of the spring engage when the spring is compressed and the valve is off its seat, whereby lateral deflection of the spring is restrained. 85

3. In an internal combustion engine, the combination of a valve having a stem, controlling communication between the cylinder and a chamber, a valve stem guide extending from the chamber having a hole in which the stem has a sliding gas tight fit, a spring surrounding the stem and acting at one end against said guide, a bearing disk for the other end of the spring loosely mounted upon the stem to transmit pressure from the spring to the stem through which the stem passes, a clearance space existing between the stem and the bearing that permits relative lateral movement of the bearing without contact with the stem, a loose connection between the bearing and the stem that permits such lateral movement, and means supporting said disk against sidewise thrust and with which the coils of the spring engage when the spring is compressed and the valve is off its seat, whereby lateral deflection of the spring is restrained. 100

4. In an internal combustion engine, the combination of a valve having a valve stem, a valve stem guide, an expansively acting coil spring surrounding the stem having a fixed bearing at one end, a bearing for the other end of the spring loosely mounted upon the stem to transmit pressure from the spring to the stem, said bearing having guiding contact with said guide, the coils of 110

the spring engaging with the guide sides when the spring is compressed, and the valve is off its seat, whereby the spring is restrained from lateral deflection, and a second coil spring within the other and interposed between the same bearings.

5. In an internal combustion engine, the combination of a valve having a valve stem, a valve stem guide, an expansively acting 10 coil spring surrounding the stem having a fixed bearing at one end, a bearing for the other end of the spring loosely mounted upon the stem to transmit pressure from the spring to the stem, said bearing having a 15 guiding contact with said guide, the coils of the spring engaging with the guide sides when the spring is compressed, and the valve is off its seat, whereby the spring is restrained from lateral deflection, and a second 20 coil spring within the other and interposed between the same bearings, the two springs having their coils of opposite pitch.

6. The combination in an internal combustion engine of a puppet valve, a stem, a 25 member with a hole through which the stem slides, a coil spring within the member, acting to seat the valve, and encircling the stem, a spring-engaging disk in said member having a hole through which the stem passes, 30 and a cross key engaging the stem and situated on the side of the disk opposite the spring, said member having its wall notched to register with the key to provide space for the endwise movement of the key in assem-

bling the parts, and means to prevent end- 35 wise movement of the key when the parts are assembled for the passage of said key.

7. The combination in an internal combustion engine of a valve-controlled passage in communication with the cylinder, a valve 40 situated in such passage, a stem reaching from the valve through the passage and to the exterior thereof through a gas tight guide, a coiled spring through which the stem passes, a relatively stationary bearing 45 for one end of the spring, a bearing for the other end of the spring movable with the stem in both directions, said bearing having a hole through which the stem passes substantially larger in diameter than the stem 50 to permit lateral movement without contact of stem and bearing, and a guide engaging the outside of the bearing.

8. In an internal combustion engine, the combination of a valve having a stem, controlling communication between the cylinder and a chamber, a valve stem guide extending from the chamber having a hole in which the stem has a gas tight fit, a spring surrounding said guide and the stem acting at 60 one end against said guide, a bearing disk for the other end of the spring loosely mounted upon the stem to transmit pressure from the spring to the stem, and means supporting said disk against sidewise thrust. 65

In testimony that I claim the foregoing I have hereunto set my hand.

FRANK D. SHEPHERD.
